VEGETABLE SLICER

Mortimer M. Wolff, Atlantic City, N. J.

Application July 17, 1950, Serial No. 11,223

Term of patent 14 years

(Cl. D89—1)

To all whom it may concern:

Be it known that I, Mortimer M. Wolff, a citizen of the United States, residing at Atlantic City, in the county of Atlantic and State of New Jersey, have invented a new, original, and ornamental Design for a Vegetable Slicer, of which the following is a specification, reference being had to the accompanying drawing, forming part thereof.

I claim:

The ornamental design for a vegetable slicer, as shown.

MORTIMER M. WOLFF.
